JOHN GEORGE LEYNER, OF DENVER, COLORADO, ASSIGNOR TO THE J. GEO. LEYNER ENGINEERING WORKS COMPANY, OF LITTLETON, COLORADO, A CORPORATION OF COLORADO.

OIL-BURNING FORGE.

1,078,154.

Specification of Letters Patent. Patented Nov. 11, 1913.

Application filed November 5, 1912. Serial No. 729,596.

To all whom it may concern:

Be it known that I, JOHN GEORGE LEYNER, a citizen of the United States, residing at Denver, in the county of Denver and State of Colorado, have invented a certain new and useful Improvement in Oil-Burning Forges, of which the following is a specification.

This invention relates to oil burning forges for heating drill steels or similar articles and more particularly to the construction of the combustion chamber of such forges.

The object of the present invention is to provide a forge in which the combustion of the fuel will be completely carried out and the flame from the blower will be applied to the articles to be heated in the most effective and economical manner. With this object in view I have devised a forge the practical embodiment of which is shown in the accompanying drawings in which:

Figure 1 is a side elevation partly in section, of the whole forge, Fig. 2 is an end elevation partly in section, on the line 2—2 of Fig. 1 and Fig. 3 is a partial plan view of the forge with the cover removed.

The forge as shown comprises a column 1 upon the upper end of which are secured the two halves 2, 3, of the outer shell of the combustion chamber 4 of the forge these halves of the shell being secured together by bolts 5. Inside of this shell is secured the lining of the combustion chamber which consists of two sections 6, 7, of refractory material such as fire brick. These sections together form a chamber the ends of which are semicylindrical in shape and from the elongated sides of which project opposite ridges 8, 9, with concave faces whose radii and centers of curvature approximate those of the semicylindrical ends, the whole giving a space practically consisting of two intersecting cylinders. The upper ends of the ridges 8, 9, are inclined outwardly so that at the top of the combustion chamber its sides are straight. Over the combustion chamber proper is placed a cover consisting of an outer metal casing 10 with a concave interior surface, in the opposite sides of which are registering apertures 11, 12 extending nearly to the top of the casing. Concave lining blocks 13, 14 are placed in the ends of the cover and are held in place by a rectangular key block 15 of refractory material which has oblique faces 55 engaging the upper edges of the end blocks 13, 14. This key block 15 passes entirely through the apertures 11 and 12 and projects beyond the cover casing on each side leaving openings 16, 17 leading to the combustion chamber through which the article to be heated can be inserted. To introduce the heating flame into the combustion chamber a cylindrical bore 18 is provided in the front of the combustion chamber which 60 passes through the lining of the chamber and the outer shell. This bore is cut directly through the ridge 8 in the combustion chamber and the center of its opening is in alignment with the edge of the opposite ridge 9. 65 An oil burner 19 of ordinary construction, the details of which form no part of the present invention, is secured outside of the chamber, its nozzle 20 being alined to direct the flame through the bore 18 directly on to 70 the edge of the opposite ridge 9. The oil burner is provided with fuel and air through fuel pipe 21 and air pipe 22 controlled by the usual valves, 23 and 24. To support the drill steels or other articles to be heated a 75 rectangular rest bar 25 is secured in brackets 26, 27 on the front of the forge the upper edge of the bar 25 being slightly above the edge of the combustion chamber casing. A 80 outer rest bar 28 parallel to and longer than 85 rest bar 25 is provided which is secured in place by arms 29 and 30 which slide in bearing sleeves 31, 32 on the ends of the combustion chamber casing and which can be held in any desired position by set screws 33. 90

To prevent the flame from coming out of the front aperture of the forge and burning the operator a flame blower is provided which consists of a transverse pipe 34 parallel to and below the rest bar 25 which is 95 provided with a series of air jet holes 35 directed toward the opening of the combustion chamber. This pipe is connected to the air supply pipe 22 by a pipe 36 and the flow of air controlled by a valve 37. A screen 38 100 is also held in perpendicular alinement with the rest bar by arms 39 adjustably secured in the cover casing 10.

The operation of the forge will be evident from the showing and description. The 105 particular advantage of the present invention however is derived from the shape of the combustion chamber. The flame enter-

ing through the aperture in the ridge 8 passes across the combustion chamber and strikes the edge of the ridge 9. The nozzle of the burner is so alined that the flame is evenly divided and follows the walls of the combustion chamber around in both directions. It is thus given a circular motion and travels in a double ascending spiral to the top of the chamber where it encounters the articles to be heated. In this way the flame is thoroughly distributed throughout the whole combustion chamber and the flame has sufficient time and length of travel before it reaches the articles to be heated to allow complete combustion of the fuel, thus adding greatly to the efficiency of the forge.

Although the present furnace is designed for burning oil, it is evident that the invention could be adapted for use with any sort of fuel which can be projected through a directing nozzle whether liquid or solid and it is to be understood that the present showing and description discloses only one specified modification of my invention and other forms and modifications are included in the

spirit and scope of the invention as expressed in the claims.

What I claim is:

1. In an oil burning forge, an elongated combustion chamber having rounded ends, a vertical ridge on one of the side walls of the chamber, a second vertical ridge on the opposite side wall, having an aperture there-through, and a fuel burner adapted to direct its flame through said aperture against the opposite ridge.

2. In an oil burning forge, a combustion chamber having its interior in the shape of a pair of intersecting cylinders with projecting ridges on opposite sides of the chamber, an aperture through one of said projecting ridges, and a burner arranged to direct its flame through said aperture on to the edge of the opposite ridge said ridge serving to divide the flame.

In testimony whereof, I have hereunto set my hand.

JOHN GEORGE LEYNER.
